UNITED STATES PATENT OFFICE.

HORATIO G. GILLMOR, OF WASHINGTON, DISTRICT OF COLUMBIA.

RAIL ANCHOR.

Application filed August 12, 1924. Serial No. 731,614.

To all whom it may concern:

Be it known that I, HORATIO G. GILLMOR, a citizen of the United States, residing at Washington, in the District of Columbia, have invented certain new and useful Improvements in Rail Anchors, of which the following is a specification.

My invention relates to devices for resisting the longitudinal creeping movement of railroad rails. Such devices are commonly known as rail anchors, anticreepers, creep-checks or rail stays.

One of the objects of my invention is to produce a device of this character which may be easily and cheaply manufactured from a rolled steel bar.

Other objects of the invention are to produce a device which will be simple in construction, easily applied with the tools ordinarily employed by track workers, and readily removed, when removal is desired, with the same tools; to produce a device which will firmly and reliably grip the rail and retain its position thereon, without being loosened or its efficiency impaired by contraction or expansion of the rail, freezing of the ballast or other effects of weather conditions, vibrations or any of the other causes tending to loosen the grip or impair the efficiency of devices of this character; and to produce a device which may be repeatedly removed, when desired, from the rail and reapplied to the same or another rail repeatedly and be tight and efficient in preventing creeping after such repeated removal and reapplication.

In order that my invention may be fully understood, I have described, as an example, one embodiment thereof in the following specification and shown the same in the accompanying drawing, in which:

Figure 1 is an elevation, with the rail in section, Figure 2 a side elevation, with the crosstie in section, showing the device in position, and Figures 3 and 4 are elevations, with the rail in section, illustrating the method of applying the device to the rail.

Like characters of reference refer to like parts in the several figures.

The form of rail anchor shown in the drawing consists of a steel rolled bar, the body portion A being arranged to extend transversely beneath, some distance below and out of contact with the base flange B of the rail. The two ends of the bar are bent to form a short arm C and a relatively

long arm D the latter having an end E formed to engage the under surface of the rail head N at one side of the rail and a surface F formed to engage the upper surface 60 of the rail base flange B at the same side of the rail. The end surface E and the surface F of the arm D are so formed that the arm D is adapted to seat within the fishing space between the head and base flange of the rail. 65 The short arm C is of such length, and so formed and related to the body A and the long arm D, that when the device is in its unstressed condition the upper portion of the arm C will come within the plane of the 70 vertical edge of the base flange B, and when the device is in final position upon the rail, and subject to the stresses set up in the device in applying it to the rail, the arm C will project slightly above the base flange 75 B and engage the upper corner G of the base flange B. Either face H of the body A may be engaged with a tie I. The curved portions K and L of the bar are formed to provide the clearances necessary for placing 80 the device in operative position. The corners of the upper portion of the arm D are rounded at M, either by locally rounding these corners or by giving the upper portion of the bar forming the arm D some curvature, to permit the upper end of the arm D to be brought closer to the center plane of the rail while being applied, and facilitate application of the device to the rail. 85

In applying the rail anchor to a rail the body A is placed underneath the rail with the rail anchor inclined to the vertical, so that the arm D may be brought at its upper end close to the web of the rail at one side and the upper corner of the arm C will then 90 be slightly beyond the edge of the rail base flange B at the other side of the rail. The position of the rail anchor will then be about as shown in Figure 3. The arm C is then raised to a position projecting above the rail base B, and the rail anchor can then be brought to a vertical position with the rail base B loosely embraced. The rail anchor is then moved longitudinally on the rail until the body A has one of its faces H in contact 95 with a tie I. Angular movement of the rail anchor in relation to the rail will then bring the rail anchor to the position illustrated in Figure 4, with the end E of the arm D beginning to engage the under surface of the 100 head N of the rail, the portion F of the arm D engaging the upper corner of the base 105 110

flange B at one side of the rail and the arm C engaging the upper corner of the base flange B at its other side. To get the rail anchor from this preliminary position shown in Figure 4 to the final operative position shown in Figure 1 force will be necessary and this may best be applied as by blows of a hammer, or other similar implement, directed against the arm D laterally, driving the arm D into the fishing space between the head N and base flange B, and directed against the end of the arm C downwardly. The rail anchor is in this manner forced to move angularly and transversely upon the rail until the operative position shown in Figure 1 is reached. When in this position the arm D is wedged securely in the fishing space between the head and base of the rail, and the arm C and the body A have been forced to assume a form and relation to the arm D differing from that found in the rail anchor in its initial unstressed condition, whereby the arm C, by its engagement with the upper corner G of the base flange B, exerts a strong gripping pressure upon the rail base B separable into transverse and vertical components. The rail is thus firmly gripped by the rail anchor.

The direction in which the rail tends to creep is indicated by the arrow on Figure 2. Contact of the surface H of the body A with the tie I prevents forward movement of the rail anchor and the grip of the arm D, wedged into the fishing space at one side, upon the head and base of the rail at that side, and of the arm C upon the rail base at the other side of the rail will hold the rail in place and effectively prevent creeping.

It will readily be seen that the rail anchor described may be easily and cheaply manufactured from a bar of steel and that it may be applied to a rail with ease using only the usual tools placed in the hands of the least skilled track mechanics and laborers.

While I have described in the foregoing specification one form of rail anchor embodying my invention, I wish it understood that changes may be made in the details thereof without departing from the scope of the invention as defined by the appended claims.

I claim:

1. A rail anchor comprising a body adapted to bear against a cross tie and to be out of contact with a rail base and end portions disposed so as to engage and grip the head and base of a rail at one side and to exert downward pressure upon the rail base at the other side of the rail.

2. A one piece anticreeper comprising a bar adapted to engage a tie in opposition to the tendency of a rail to creep, provided with end arms, one of which is adapted to be wedged in between the head and base of a rail at one side and the other of which is

adapted to exert downward pressure upon the rail base at the other side of the rail.

3. A device for preventing the creeping of rails comprising a body adapted to engage a cross tie, and two arms of unequal length so disposed that said device may be preliminarily positioned upon a rail and then, by forced angular movement transversely upon the rail, the longer of said arms may be made to exert gripping pressure upwardly upon the head and downwardly upon the base of the rail at one side and the shorter of said arms be made to exert downward gripping pressure upon the base at the other side of the rail.

4. An anticreeper comprising a body, and upwardly and inwardly extending arms so arranged that lateral clearance is provided for applying the device to a rail with the body contacting with a crosstie and with the arms in preliminary engagement with the head at one side and with the upper corners of the base at both sides of the rail, and so arranged that the device is movable angularly transversely of the rail from its position of preliminary engagement into its operative engaging position and is thereby forced into strong gripping engagement with the head and base at one side and with the upper corner of the base at the other side of the rail.

5. A rail anchor comprising a body and arms extending upwardly substantially in the plane with the body, being so arranged that clearance is provided for applying the device without distortion to a rail with the body extending across below but out of contact with the base and with the arms in preliminary engagement with the head of the rail at one side and with the upper corners of the rail base at both sides of the rail, the parts being so positioned and proportioned that upon angular movement of the device upon the rail into its operative position the device is forced to exert strong downward gripping pressure upon the rail base at both sides and upward gripping pressure upon the rail head at one side of the rail.

6. An anticreeper comprising a body, and end arms formed integrally with the body and extending upwardly and inwardly toward each other, one of said arms being formed with a portion adapted to engage the under side of the rail head and to provide clearance for permitting the device to be applied transversely of the rail into preliminary position at right angles with respect to the rail along one face of a cross tie without springing the arms outwardly with respect to each other, the arrangement and proportions of the parts being such that a forcible transverse angular movement of the device from its preliminary to its operative position causes the arms to exert up-

ward gripping pressure upon the rail head at one side and downward gripping pressure upon the rail base at both sides of the rail.

7. A rail anchor comprising a body member engageable with a cross tie, and terminal gripping arms formed with the body member and adapted to engage a rail head at one side and the upper portion of the rail base at both sides of the rail for securing said rail anchor to the rail, said terminal arms being so disposed with relation to each other and said body member as to be tightened upon the rail by movement together angularly in a plane transverse to the rail.

15 8. An anticreeper comprising a member adapted to engage a cross tie, but not the bottom of a rail base, and bent to form end arms for engaging the head at one side and the top of the rail base at both sides of the rail and to provide interior clearance to permit the preliminary positioning of said anticreeper on the rail, said arms being so disposed in relation to each other as to necessitate distortion of said anticreeper for 25 movement thereof from preliminary position to operative engagement.

9. A device for preventing the creeping of rails comprising a body adapted to bear against a cross tie below and out of contact

with a rail base, an arm wedged in between the head and base of the rail at one side, and a second arm pressing downwardly upon the base at the other side of the rail.

10. A one piece anticreeper comprising a body out of contact with the bottom of a rail when applied in operative position thereto, and end arms substantially in the same plane with the body serving by heavy downward pressure upon the rail base at both sides and by heavy upward pressure upon the rail head at one side of the rail to cause the anticreeper very strongly to grip the rail independently of any pressure on either face of the body longitudinally of the rail.

15 11. A rail anchor comprising a body contacting with a tie but not with the rail base below a rail when in operative position on a rail, and end arms extending inwardly and upwardly substantially in the plane with the body and serving by direct engagement with the rail head at one side and with the top of the rail base at both sides of the rail to apply pressure thereto for causing the device to strongly grip the rail independently 55 of any pressure on either face of the body longitudinally of the rail.

H. G. GILLMOR.
